UNITED STATES PATENT OFFICE.

MORRIS KEEN, OF ATLANTIC CITY, NEW JERSEY, ASSIGNOR TO KEEN-O-PHONE COMPANY, A CORPORATION OF DELAWARE.

DESIGN FOR A CABINET FOR SOUND-REPRODUCING MACHINES.

43,962.

Specification for Design.

Patented May 6, 1913.

Application filed January 22, 1913. Serial No. 743,663. Term of patent 14 years.

To all whom it may concern:

Be it known that I, MORRIS KEEN, a citizen of the United States, residing at Atlantic City, in the county of Atlantic and State of New Jersey, have invented a new, original, and ornamental Design for a Cabinet for Sound-Reproducing Machines, of which the following is a specification, reference being had to the accompanying drawing, forming part thereof.

The figure is a perspective view of a cabinet for sound reproducing machines showing my new design.

I claim:

The ornamental design for a cabinet for sound reproducing machine, as shown.

MORRIS KEEN.
